UNITED STATES PATENT OFFICE

123,307

DESIGN FOR AN AIRPLANE

Athanas P. Fontaine, Nashville, Tenn., assignor
to Aviation Manufacturing Corporation, New
York, N. Y., a corporation of Delaware

Application July 12, 1940, Serial No. 93,594

Term of patent 7 years

To all whom it may concern:

Be it known that I, Athanas P. Fontaine, a citizen of the United States, residing at Nashville, in the county of Davidson and State of Tennessee, have invented a new, original, and ornamental Design for an Airplane, of which the following is a specification, reference being had to the accompanying drawings, forming a part thereof.

In the drawings:

Figure 1 is a top plan view of an airplane, showing my new design;

Figure 2 is a front elevational view; and

Figure 3 is a side elevational view, on a somewhat enlarged scale.

I claim:

The ornamental design for an airplane, substantially as shown.

ATHANAS P. FONTAINE.
